BAILER OR SAND PUMP

William A. Larson, Centralia, Ill., and Harry T. Swortwood, Oklahoma City, Okla.

Application August 4, 1939, Serial No. 288,356

4 Claims. (Cl. 166—19)

The invention herein described is an improvement over the related inventions covered by United States Patent No. 2,090,209, issued August 17, 1937, and by patent application Serial No. 5 176,796, filed November 27, 1937, now Patent No. 2,176,231, granted Oct. 17, 1939, and relates to bailers, sand pumps, or plunger type pumps, and more particularly to plungers for such pumps.

It is the chief object of the invention to provide a bailer or sand pump which has the following combined advantageous features: a cable operated plunger which leaves a comparatively large and unobstructed fluid passage area immediately above the plunger in the barrel, as opposed to the necessarily restricted passage area in the solid rod operated plunger type pump, the larger passage area greatly reducing the chances of the plunger sticking due to sand settling on top of the plunger; a swivel connection 10 between cable and plunger to prevent kinking of the cable during hard spudding; a rope socket connection between cable and swivel to prevent accidental loss of the bailer or pump in the well; a plunger sealing element which is easily and quickly replaceable without welding and without taking the entire plunger to a machine shop; a weighted one-way plunger valve which is positively held open by the weight as the plunger passes downward in the barrel, yet which is positively held closed during the upstroke; a combination plunger valve head and swivel connection member which is replaceable easily and quickly; a weight below the sealing element which serves not only to pull the plunger downward 35 through fluid in the barrel, but which also serves to prevent the sealing element from reaching the extremely heavy sand-laden fluid at the bottom of the barrel, which fluid often sticks sand pump plungers at the beginning of the upstroke; and a jar which aids in dislodging the entire plunger in case it becomes stuck in the barrel.

The details in the construction of a preferred form of this invention, together with other objects attending its production will be better understood from the following description when read in connection with the accompanying drawing, which is chosen for illustrative purposes only, and in which,

Figure 1 is a vertical sectional view through a sand pump embodying the invention, and shows a preferred type of plunger in position within a pump barrel, the usual head and valved bottom for the barrel being omitted;

Figures 2, 3, 4 and 5, are horizontal sectional

views taken respectively along the lines 2—2, 3—3, 4—4, and 5—5 of Figure 1.

Like characters of reference designate like parts in all the figures.

The sand pump embodying the invention includes the usual tubular barrel 6, provided at its upper end with the suitable head (not shown), and provided at its lower end with a suitable valved bottom (not shown).

The pump plunger is made up of two main parts, the sealing element, which is designated as a whole by the numeral 7, and a combination valve head guide and plunger weight, which is designated as a whole by the numeral 8. The sealing element 7 is made in the form of a sleeve, the diameter of the longitudinal bore through the sleeve being enlarged intermediate its ends to form a cavity 9. A side entrance 10 is provided adjacent the cavity 9 by cutting away a portion of the wall of the sleeve. This cavity 9 and its side entrance 10 serves to permit a valve head 11 and its stem 12 to enter the lower end of the sleeve without the use of tools of any kind. It will be noted that the length of the cavity 9 is approximately twice the length of the valve head 11 so that longitudinal movement of the valve head 11 is permitted within the lower end of the sleeve.

The valve head stem 12 is integral with a combination valve head guide and plunger weight 8, as is clearly shown in Figure 1. The valve head is of considerably larger diameter than the stem 12. The member 8 is provided with a plurality of longitudinally extending radially projecting circumferentially spaced guides 13, which serve to contact the walls of the barrel 6 and to thus maintain the member 8 and the valve head 11 in a concentric position therein. Preferably, the member 8 is considerably longer than the sleeve 7, and due to its size it exerts considerable weight on the valve head 11, tending to keep the valve head at the lower end of the cavity 9 during the downstroke of the plunger. The lower end of the member 8 is provided with a plurality of slots 14, which serve as fluid passages. It is also provided with a portion of enlarged diameter 15, which serves to contact the interior wall of the barrel 6 in a manner similar to the guides 13, and to serve as additional guide for this member. The valve head 11, its stem 12, and the upper portion of the member 8 are longitudinally bored to receive a flexible plunger reciprocating element 16, which, in the drawing, has been illustrated as a wire cable. A rope socket 17 is formed intermediate the ends of 55

the member 8, and the lower end of the cable 16 is babbitted in this socket in the usual manner.

A valve seat 18 is formed in the sealing element 7 at the upper end of the cavity 9 and serves to seat the valve head 11 as the entire plunger is moved upward in its barrel by means of the cable 16. A piston ring 19 located above the valve seat 18 serves to seal against the walls 10 of the barrel 6.

In operation it will be seen that the entire sand pump may be lowered into a well and that fluid is free to pass into the usual check valve in the bottom of the pump barrel 6, upward through the barrel past the guides 15, through the slots 14, thence through the annular space surrounding the member 8 upward through the passage 10, the cavity 9, and the reduced sleeve bore above the cavity 9. The frictional contact of the sealing element 7 with the walls of the barrel 6 will ordinarily be sufficient to maintain the member 8 and the sleeve 7 in the relative positions shown in Figure 1 of the drawing except during the up-stroke of the plunger.

25 When the bottom of the bailer sets on the bottom of the well, the entire plunger moves downward through any fluid which may be in the barrel, until the lower end of the member 8 contacts the bailer bottom. The length of the member 8 naturally limits the approach of the sealing element 7 toward the bottom of the bailer, thus holding the sealing element 7 above the fluid which is most heavily laden with sand. At the beginning of the up stroke of the plunger, 30 the head 11 seats on its seat and the fluid in the barrel above the plunger is forced out through ports or through the head of the barrel, while sand laden fluid is drawn in through the valved bottom of the barrel. The plunger may be reciprocated several times, and additional sand laden fluid drawn in through the bottom each time. Each stroke of the plunger, however, would ordinarily be of less length than the previous stroke due to the fact that a considerable 35 amount of sand settles to the bottom of the fluid within the barrel. The entire barrel is then withdrawn from the well and the sand laden fluid emptied and the bailing process repeated until the well is substantially free of sand at its bottom.

40 It will be seen that with the construction described there has been provided a swivel means for attaching the operating cable to the plunger, a weight means below the sealing element (where it is most practical) for holding the plunger valve open when the plunger operating element is slack; a pump in which the upper end of the barrel above the plunger is comparatively unobstructed, being occupied only by a cable of 45 comparatively small diameter; and a pump in which the sealing element proper is not permitted to actually reach the fluid at the extreme bottom of the pump, which fluid is, of course, most heavily laden with sand and often causes the 50 plunger to stick near the end of the downstroke.

55 While a specific embodiment of the invention has been described, it will be understood that numerous alterations and changes may be made therein and it is not intended that the invention 60 should be limited, except by the prior art and by the scope of the appended claims.

We claim:

1. In a bailer or sand pump, a plunger comprising: a sleeve-like sealing element having a 65 comparatively large valve cavity intermediate its

ends communicating with a pair of smaller longitudinally extending aligned bore holes, the outer ends of which extend to the extreme opposite ends of the element; a combination valve head guide and plunger weight having an integral valve stem formed at its upper end, said stem being of a cross sectional size and shape to freely rotate and slide within the bore hole in the lower end of said sealing element; and a valve head rigidly secured to the upper end of said stem and reciprocable and rotatable within said valve cavity for effecting a swivel connection between the sealing element and the weight; and plunger operating means connected to said weight and extending upward through the bore hole in the 15 upper end of said sealing element.

2. In a bailer or sand pump, a plunger comprising: a sleeve-like sealing element having a comparatively large valve cavity intermediate its ends communicating with a pair of smaller longitudinally extending aligned bore holes, the outer ends of which extend to the extreme opposite ends of the element; a combination valve head guide and plunger weight having an integral valve stem formed at its upper end, said stem being of a cross sectional size and shape to freely rotate and slide within the bore hole in the lower end of said sealing element; and a valve head rigidly secured to the upper end of said stem and reciprocable and rotatable within said valve cavity 20 for effecting a swivel connection between the sealing element and the weight; and a rope socket extending through said valve head, said valve stem, and into said guide and weight; and a flexible plunger operating element secured firmly in said rope socket and extending upward through the bore hole in the upper end of said sealing element, and slideable therethrough.

3. In a bailer or sand pump, a plunger comprising: a sleeve-like sealing element having a pair of comparatively small concentric longitudinally extending bores in its opposite ends communicating with an enlarged substantially cylindrical concentric cavity located intermediate the ends of said element; a valve head reciprocable and rotatable within said enlarged cavity, said head having a larger cross sectional area than either of the small concentric bores in said element; a valve seat formed at the upper end of said cavity for seating said valve head; a valve stem connected rigidly to said head and protruding from the lower end of said sealing element and reciprocable and rotatable within the small bore therein; a combination valve head guide and plunger weight rigidly connected to said valve stem and extending for a considerable distance therebelow; and a flexible element having one end secured to said guide and plunger weight and extending upward through said stem, said valve head, said enlarged cavity, and the small bore in the upper end of said sealing element for operating the plunger.

4. In a bailer or sand pump, a plunger comprising: a sleeve-like sealing element having a comparatively large valve cavity located intermediate its ends and communicating with the inner ends of a pair of smaller longitudinally extending aligned bore holes, the outer ends of which extend to the extreme opposite ends of the element; a valve seat formed at the upper end of said valve cavity; a valve head reciprocable and rotatable within said valve cavity only; an elongated combination valve head guide and plunger weight having its upper end slidably and rotatably extending through the bore hole in the 70 75 80 85 90 95 100

lower end of said sealing element and rigidly connected to said valve head, the latter thus effecting a swivel connection between the sealing element and the combination guide and weight; 5 and plunger operating means secured to the combination guide and weight and extending up-

ward through the bore hole in the upper end of said sealing element, said means also adapted to effect the seating of said valve head on its seat.
